UNITED STATES PATENT OFFICE.

ANDREW H. SACKSTEDER, OF TIFFIN, OHIO.

WASHING MACHINE.

Application filed February 15, 1922. Serial No. 536,771.

To all whom it may concern:

Be it known that I, ANDREW H. SACKSTEDER, a citizen of the United States, residing at Tiffin, in the county of Seneca and 5 State of Ohio, have invented certain new and useful Improvements in Washing Machines, of which the following is a specification.

This invention relates to washing machines and has for an object the provision of means whereby clothes may be agitated within a tub to be subjected to the action of water and a cleansing agent and subsequently partly dried through centrifugal action. 10 The invention also has for an object the provision of simple and easily controlled means whereby the speed of rotation of the clothes container may be regulated, and a further object of the invention is to provide means 15 whereby a clothes container may be operated within a plurality of tubs successively without removing the clothes from the container. Other objects of the invention will appear in the course of the following description, 20 and the invention resides in certain novel features which will be particularly pointed out in the claims following the description.

In the accompanying drawings—

Figure 1 is a plan view of one embodiment 30 of the invention;

Fig. 2 is a view, partly in side elevation and partly in vertical section, of the apparatus shown in Fig. 1;

Fig. 3 is an enlarged plan view of the 35 driving mechanism, the cover of the casing being removed;

Fig. 4 is an enlarged longitudinal section of the driving mechanism;

Figs. 5 and 6 are, respectively, a horizontal section and a vertical section taken longitudinally of another form of driving 40 gearing.

In carrying out the invention, I employ a supporting frame 1 which includes legs 2 45 disposed at the corners of the supporting frame whereby to maintain the same in a substantially horizontal position. The legs are connected by a shelf or brace 3 upon which an electric motor 4 is secured, current being supplied to the motor from any convenient source. The frame 1 comprises a plurality of rings 5 having outstanding flanges 6 and adapted to receive tubs 7, the tubs being equipped upon their sides with 50 collars or flanges 8 resting upon the flanges 6 of the rings 5 so that they will be effectu-

ally supported. The several rings 5 of the frame are connected by a central brace or platform 9 which is constructed with a sleeve 10 forming a bearing for the main driving shaft 11, the lower end of said shaft being fitted in a step bearing 12 on the shelf 3, as clearly shown in Fig. 2. The shaft of the motor 4 is equipped at its inner end with a beveled pinion 13 meshing with a beveled pinion 14 fixed upon the shaft 11 so that the said shaft will be rotated directly by the motor, and, at a point above the plane of the tops of the tubs, a beveled gear 15 is secured upon the main driving shaft and is adapted 60 to mesh with similar gears 16 carried by shafts 17 which extend into gear casings 18 disposed on prolongations of the radii of the driving shaft 11 and arranged to extend radially over the respective tubs. In the 65 bottom of each gear casing, at the outer end thereof, is journaled a spindle 19 which has secured to its lower end a spider 20 from which a reticulated basket or clothes container 21 depends, the spider and the basket being of less diameter than the tubs so that 70 they may fit concentrically within a tub and rotate easily therein. A cover 22 is secured to the spindle 19 just below the gear casing 75 and is adapted to fit closely within the tub and be removed therefrom with the spindle and the basket as will presently more fully appear. Near the outer end of the gear casing, a partition 23 is provided therein and this partition has a cam edge 24 80 formed thereon and disposed concentrically with the spindle 19 and its bearing. A beveled pinion 25 is feathered upon the spindle 19 and rests upon the bearing for 85 said spindle, said pinion meshing with a pinion 26 on the outer end of a shaft 27 which is disposed in axial alinement with the shaft 17 and is journaled in the lower portion of the partition 23, as shown in Fig. 90 4. A clutch coupling 28 is fitted upon the adjacent ends of the shafts 17 and 27 and constitutes a connection between the same so that the shaft 27 may be driven directly from the shaft 17 at a high speed or may be driven indirectly therefrom at a lower speed. Journaled in the inner end of the gear casing 100 18 vertically above the shaft 17 is a shaft 29, and journaled in the partition 23 vertically above the shaft 27 is a shaft 30 which is alined axially with the shaft 29, a clutch coupling 31 connecting the said shafts 105 29 and 30 in the same manner that the 110

clutch 28 connects the shafts 17 and 27. Upon the shaft 17 within the gear casing is secured a gear 32 which meshes with a gear 33 secured upon the shaft 29 and upon the shaft 27 adjacent the partition 23 is secured a gear 34 meshing with a gear 35 secured upon the shaft 30. The clutch couplings 28 and 31 are provided exteriorly with annular grooves 36 which are engaged by forks 37 carried by a lever 38 provided with a handle member 39 extending through the side of the gear casing. The lever is so disposed that the clutch couplings 28 and 31 will be moved in opposite directions simultaneously and when the said couplings are in vertical alinement the several shafts will be disconnected so that no motion will be imparted to the shaft 27. If the lower clutch coupling 28 be closed, the shafts 17 and 27 will be coupled and the shafts 28 and 30 uncoupled so that motion will then be imparted to the shaft 27 directly from the shaft 17 and this motion will be transmitted through the gears 26 and 25 to the spindle 19 so that the basket or clothes container will be rotated within the tub. If the lever 38 be set so that the coupling 28 is opened and the coupling 31 closed, the shaft 27 will be free of the shaft 17, but the shafts 29 and 30 will then be connected and the motion of the shaft 17 will be transmitted through the gears 32, 33, 35 and 34 to the shaft 27 and said shaft 27 will then rotate at a lower speed, the spindle 19 being, of course, given a lower speed.

Secured to the shaft 19, above the gear 25, is a collar 40 having an external projection upon which is carried a roller 41. The roller 41 travels upon the cam surface 24 of the partition 23 and, consequently, as the spindle 19 is rotated it is also moved vertically so that the basket 21 will be raised and lowered and the clothes within the basket thereby moved vertically through the water and cleansing agent within the tub as well as rotated therein and the entire surfaces of the clothes will be subjected to the washing action. Above the collar 40, a hub or collar 42 is fitted upon the spindle 19 and this hub or collar constitutes a support for roller bearings 43 which may be of any well-known form. Pivoted to the lever 38 and slidably mounted in the upper end of the partition 23 is a locking fork 44 which will be projected outwardly when the clutch couplings are shifted so as to drive the shaft 27 at the higher speed. If, when the spindle 19 has been raised to its highest level by the travel of the roller 41 upon the cam edge 24 of the partition, the clutch couplings be shifted, the fork 44 will engage under the projection 42 and will thereby hold the same at rest so that the spindle and the basket carried thereby will be supported in the high position. If the motor

be then started, the basket will be rotated at a high speed above the level of the water in the tub and the loose water upon the clothes will be thrown off by centrifugal action.

Upon the inner ends of the gear casings, at the upper and lower corners thereof, are lugs or projections 45 and 46 and through the said projections extend vertically disposed rods 47 and 48, the rods 48 being threaded and equipped at their upper ends with hand wheels 49. The lugs 45 and 46 engaged by the threaded rods are, of course, provided with internally threaded bores so that, when the threaded rods are rotated, the gear casings will be caused to move vertically. The extremities of the rods 47 and 48 are journaled in bearing blocks 50 which are loosely fitted about the main driving shaft 11 and held against dropping thereon by any convenient means, such as a stop collar 51. If the threaded rods 48 be rotated in the proper direction through manipulation of the respective hand wheels 49, the gear casings will be caused to move upwardly and the pinions 16 will be raised out of mesh with the driving pinion 15, as will be readily understood. The basket 21 will, of course, be withdrawn from the tub in which it has operated and the cover 22 will be likewise removed from said tub. The gear casing, the basket and the parts associated therewith may then be swung about the main driving shaft 11 as a center and the basket then lowered into an adjacent tub, it being noted, upon reference to the drawings, that, in the particular embodiment of the invention illustrated, there are three tubs and two baskets and trains of gearing for operating the baskets. This arrangement permits the several steps in the washing and drying of the clothes to be performed in series so that the baskets or clothes containers may be successively operated within a tub containing soap or other cleansing agents dissolved in water and then moved into a tub containing relatively clear water or a bleaching agent, and then moved into an empty tub in which it may be subjected to a final rotation at high speed so as to throw off all the moisture through centrifugal action. In the drawings, one clothes container is operating within the washing tub and one within the bleaching tub, while the final drying tub is not in use. When the clothes have been sufficiently agitated within the tubs in which they are deposited in the illustrated arrangement, the clothes containers are lifted and then shifted pivotally so that the tub which is illustrated as not in use will be occupied by the container holding the clothes which have been subjected to the action of the bleaching agent, and rotation of said container will then drive off the moisture from said clothes. The clothes may

then be removed from the container for further drying through exposure to the sun or the action of other heat, and if the containers be then again raised and shifted pivotally, the empty container will be in position to receive a second quantity of clothing to be washed. The operation may be repeated in a continuous cycle until all of the clothes on hand have been run through the apparatus and cleaned.

In Figs. 5 and 6, I have illustrated a form of gearing which may sometimes be preferred. In this arrangement, the main driving shaft 55 is mounted in the same manner as the shaft 11 and may be driven from an electric motor or other prime mover. Above the supporting frame, the said shaft 55 is equipped with a beveled gear 56 meshing with a beveled gear 57 on the inner end of a shaft 58 which is journaled in the inner end of a gear casing 59, the said gear casing extending over the tub in the same manner that the gear casings 18 extend over the same. The gear casings 59 are fitted to guide rods 60 and adjusting rods 61 which correspond in all respects to the rods 47 and 48 in the previously described arrangement. Upon that end of the shaft 58 which is disposed within the gear casing, is slidably fitted a friction pinion 62 which is constrained to rotate with said shaft and said friction pinion bears against the face of a friction transmission pulley 63 which is carried by a shaft 64 journaled in the side wall of the gear case 59, a spring 65, coiled about the shaft 64 between the side of the gear case and the outer face of the pulley 63, serving to hold the pulley constantly in engagement with the pinion 62 and a similar friction pinion 66. The friction pinion 66 is slidably mounted upon a shaft 67 which is alined axially with the shaft 58 and is journaled in the partition 68 near the outer end of the gear casing. The pinions 62 and 66 are constructed with hubs having annular grooves 69 therein and these grooves are engaged by forks 70 at the ends of a link 71, a handle 72 projecting laterally from the said link through a slot 73 in the side of the gear casing. It will be readily understood that the motion of the pinion 62 is transmitted to the pinion 66 through the friction disc or pulley 63 and the relative speeds of the pinions is regulated by shifting them radially upon the disc or pulley 63. This shifting or adjustment of the pinions is accomplished by moving the link 71 longitudinally of the gear casing in an obvious manner.

The outer end of the shaft 67 is equipped with a beveled pinion 74 meshing with a beveled gear 75 which is feathered upon the spindle 76 corresponding to the spindle 19 in all respects. The outer edge of the gear casing is given a cam formation, as shown at 77,

and upon the spindle 76, near the upper end thereof, is secured a collar 78 carrying a roller 79 corresponding in all respects to the collar 40 and roller 41. A collar 80 having a shoulder or projection 81 is fitted upon the spindle above the collar 78 and, above the said collar 80, roller bearings 82 are provided upon the spindle. The outer end of the gear case carries a tubular cover 83 which encloses the upper portion of the spindle 76, the gears 74 and 75, and the several members 78, 79, 80, 81 and 82, as clearly shown in Fig. 6. This tubular cover or housing is equipped with a lid 84 having openings 85 therein through which pass suspending grippers 86 which are adapted to engage under the projection 81 of the collar 80, as clearly shown in Fig. 6, and thereby support the spindle and the basket carried thereby in the elevated position. The suspending grippers 86 are pivotally mounted upon the lid 84 and their upper ends converge, as clearly shown. Disposed centrally in the lid 84 is a controlling screw 87 constructed with a head 88 and a hub 89, the hub 89 being adapted to bear upon the upper extremities of the grippers 86 so that if the screw be adjusted downwardly through the lid 84, the pressure thereby exerted upon the upper ends of the grippers will cause them to swing about their respective pivots and move their lower ends outwardly from under the projection 81 and permit the spindle and the basket or clothes container to descend. It will be readily noted that the portions of the grippers below their pivots are much greater than the portions above the pivots so that if the screw be adjusted upwardly, the weight of the grippers will cause them to swing into the position shown in Fig. 6 and engage under and support the collar 80. The washing machine equipped with this form of gearing is operated in the same manner as the machine previously described to effect cleaning of the clothes, and it will be readily noted that the apparatus is very simple in the construction and arrangement of its parts and provides mechanism whereby a large quantity of clothing may be very easily, rapidly and effectually cleaned and dried. It will, of course, be understood that gas burners or other heaters may be installed under the tubs to maintain the temperature of the liquid therein.

Having thus described the invention, what is claimed as new is:

1. In a washing machine, the combination of a tub, a vertically disposed driving shaft arranged adjacent the tub, means for rotating said shaft, a gear casing disposed over the tub, a spindle mounted in and depending from said gear casing, a clothes container carried by said spindle within the tub, gearing within the gear casing operatively connecting the driving shaft with said

spindle, and means supported on the driving shaft for raising and lowering the gear casing whereby to remove the spindle and the clothes container from the tub or dispose the spindle and clothes container within the tub.

2. In a washing machine, the combination of a vertically disposed driving shaft, a series of tubs disposed concentrically about 10 said shaft, means for rotating said shaft, supporting blocks pivotally mounted upon said shaft, gear casings disposed over the respective tubs and arranged radially with respect to the driving shaft, clothes containers carried by the gear casings and adapted to be housed within the respective tubs, gearing within the gear casings operatively connecting said clothes containers

with the driving shaft, projections on the inner ends of the gear casings, and guiding 20 and adjusting rods extending vertically through said projections and journaled in the supporting blocks pivotally mounted on the driving shaft.

3. In a washing machine, the combination 25 of a tub, a container adapted to be housed within the tub, a vertically disposed spindle carrying said container, means for rotating the spindle, a cam concentric with the spindle, a member on the spindle riding on 30 the cam, and means adjacent the high part of the cam to support the spindle in inoperative relation to the cam.

In testimony whereof I affix my signature.

ANDREW H. SACKSTEDER. [L. S.]
